UNITED STATES PATENT OFFICE.

WILLIAM MAYO VENABLE, OF PITTSBURGH, PENNSYLVANIA, ASSIGNOR TO BLAW-KNOX COMPANY, A CORPORATION OF NEW JERSEY.

SHEAVE CONSTRUCTION FOR LEVER-ARM BUCKETS.

Application filed June 6, 1925. Serial No. 35,283.

This invention relates to various improvements associated with the sheaves of a lever arm bucket and it has for its principal objects the provision of arrangements for ensuring greater dependability in operation of the bucket, longer life of the parts, better lubrication of moving surfaces, more protection from grit and dirt, greater simplicity in manufacture and assembly as well as in repair, etc.

In connection with the foregoing I wish to point out that buckets of this type are often required to work in materials which quickly fill up the scores of the sheaves in the lever arm so as to cause binding of the operating cable. This often happens, for instance, in such materials as clay, dust, bituminous coal dust, asphalt, etc. As a specific object of the invention I provide means for constantly maintaining the sheave scores in a clean condition.

I also wish to point out that in a lever arm type of bucket there are generally two sheaves in the lever arm and, during operation of the bucket these sheaves are constantly being raised and lowered so that in the absence of suitable means for automatically maintaining the scores in a clean condition, use of the bucket would have to be suspended until a cleaning operation had been effected. Furthermore there are stretches of the operating cable on either side of the sheaves and care must be taken not to interfere with the free run of the cable. These matters have all then taken care of in my improvements as will appear.

It is further desired to point out that the space available for the various parts associated with the lever arm of a bucket is very limited and that mere increase in size is not permissible in order to secure strength and long life. My improvements take this into account and give the desired results without in any way encroaching upon the available clearances.

The foregoing together with such other objects as may appear hereinafter or are incident to my invention I obtain by means of a construction which is illustrated in preferred form in the accompanying drawings, wherein

Fig. 1 is a side elevation of a lever arm bucket embodying my improvements with the bucket shown in open position and

Fig. 2 is an enlarged longitudinal section

thru the lever arm sheave pin in order to illustrate various details of the invention.

Referring to the drawings it will be seen that the lever arm 1 of the bucket is of forked construction at its outer end the spaced members 2 of which being adapted to carry between them the sheaves 3 and 4. A bushing 5 with integral end closure plate 6 is mounted in a suitable opening in each member 2. Securing bolts 7 arranged circumferentially around the pin pass through the flange 8 of the cover plate into suitable threaded openings 9 in the members 2.

A sheave pin 10 is mounted in the bushings and a sheave 4 is keyed to this pin so that the two parts rotate together, the sheaves 4 being mounted, as shown, immediately adjacent one of the bushings 5.

Between the sheave 4 and the other bushing 5 is mounted the other sheave 3 upon a rotatable bushing 11 keyed or otherwise secured to the sheave.

The operating cable 12 is reeved around the sheaves in the usual manner so that there are stretches of the cable on each side of the sheaves.

In order to maintain clean scores in the sheaves I secure the strap 13 to the upstanding lugs 14 on the members 2 and upon this strap I mount a suitable cleaning tool 15 for each sheave score which, in the present instance, takes the shape of a threaded bolt passing down thru the strap as shown with lock nuts 16 to hold them in any desired position of adjustment. These tools are preferably adjustable so as to come very close to the bottom of the sheave scores and they, together with the lugs 14 and the strap 13 are so located between the stretches of the cable 12 as not to interfere in any way with the operation of the bucket.

Lubrication is accomplished in the following manner. A longitudinal hole or passage 17 is formed in each end of the pin 10 and this connects to the transverse passages 18 arranged to discharge into the annular groove 19 in the bushing 5. Lubricant is forced in under pressure through the opening occupied by the plug 20 and after sufficient lubricant has been introduced it will be seen that there is no outlet for it except at the far or inner end of the bushing between the bushing and the side of the adjacent sheave. By forcing an excess of lubricant through the bearing in this manner it

is possible to clean out any grit or dirt which may have worked into the bearing during operation of the bucket.

It will be seen that the bushing and integral closure plate 6 provide an absolutely tight outside face, for the bearing and if the proper supply of lubricant is maintained there is practically no opportunity for dirt or grit to enter and score the bearing.

10 The bushing 11 is lubricated through a passage 21 in the sheave hub 22 of the sheave 3. The passage 21 communicates through an opening 23 with the annular groove 24 on the inside of the bushing 11.

15 It will be seen that I have provided large adequate bearings for the pin 10. This makes it possible to use a very small hub 25 for the sheave 4 which rotates with the pin and provides adequate space for the large hub 22 of the sheave 3. In this way the sheave 3 has room for an ample bearing upon the pin through its bushing 11 and it will be noted that the bottom of the sheave score is approximately over the center of this bearing. In former constructions the sheave hubs abutted approximately along the line of the adjacent sheave flanges 26 so that the load was not central over the bearings. As a consequence the bearings wore more 20 on the inside than they did on the outside and caused a wobbling of the sheaves so that their flanges 26 rubbed together and rapidly wore away. This difficulty is completely overcome by my improved construction.

30 35 The usual reeving of the cable 12 causes a rotation of the sheaves 3 and 4 in the same

direction with one sheave travelling at a greater speed than the other. It will be seen, therefore, that my improved arrangement reduces to a great degree the amount of wear incident to the rotation of the sheaves.

I claim:—

1. In a lever arm bucket, the combination of a sheave in the arm, stretches of line on each side of the sheave, and a cleaning tool supported from the arm and projecting between the stretches of said line into the score of the sheave.

2. In an excavating bucket, the combination of a sheave support, a sheave mounted therein, stretches of line on each side of the sheave, and a cleaning tool carried by said support and projecting between the stretches of said line into the score of the sheave.

3. In a lever arm bucket, the combination of a sheave in the arm, stretches of line on each side of the sheave, a support on the lever arm adjacent the sheave between the stretches of the line, and a cleaning tool carried by said support and projecting into the score of the sheave.

4. In a lever arm bucket, the combination of a sheave in the arm, stretches of operating cable on each side of the sheave, a strap on the arm between the stretches and passing over the sheave, and a cleaning tool projecting from the strap into the score of the sheave.

In testimony whereof, I have hereunto signed my name.

WILLIAM M. VENABLE.
